UNITED STATES PATENT OFFICE.

ALFRED COX, OF JULIUSTOWN, NEW JERSEY.

CULTIVATOR.

SPECIFICATION forming part of Letters Patent No. 330,211, dated November 10, 1885.

Application filed January 10, 1885. Serial No. 152,484. (No model.)

To all whom it may concern:

Be it known that I, ALFRED COX, of Julius-town, in the county of Burlington and State of New Jersey, have invented an Improved Cultivator, of which the following is a specification.

The special object of the invention is to clamp a disk-plow to and make it turn with its axle, as hereinafter described.

Figure 1 is a sectional detail view, showing the several parts of the plow or disk standard. Fig. 2 is a front elevation of the section J' of the disk-standard hereinafter described. Fig. 3 is an end view of the axle and bolt.

In the drawings, J represents one section of the disk-standard, and J' the other, the two being conjoined by a bolt and nut, j j'. In the section J' is a bearing closed at the outer end, while the section J has a bearing, of which the lower part is bolted to the upper. K represents the disk-axle, having the end journal, k, and the journal k', between the two collars k². Between these collars I also preferably fit the lower part of the bearing of section J, so

as to prevent the possibility of lateral movement in the axle. This bearing-journal is hollow, angular on the inside, and receives an angular bolt, L, threaded at the end. The disk M fits on the projecting squared part of bolt next the thread, and is clamped against the adjacent collar k². Thus it will be seen that the disk turns with the axle.

Having thus described all that is necessary to a full understanding of my invention, what I consider to be new, and propose to protect by Letters Patent, is specified in the following claim.

A two-part plow-standard, J J', provided with two bearings, of which one has a detachable part, in combination with a hollow two-collared axle, K, and a square end-threaded bolt, L, whereby a disk-plow may be clamped to and made to turn with its axle, as described.

ALFRED COX.
